UNITED STATES PATENT OFFICE.

ELLIS J. G. PHILLIPS, OF AURORA, ILLINOIS, ASSIGNOR TO RICHARDS-WILCOX MANUFACTURING COMPANY, OF AURORA, ILLINOIS, A CORPORATION OF ILLINOIS.

FOLDING DOOR.

1,377,626.

Specification of Letters Patent. Patented May 10, 1921.

Application filed May 17, 1920. Serial No. 382,011.

To all whom it may concern:

Be it known that I, ELLIS J. G. PHILLIPS, a citizen of the United States, and a resident of Aurora, in the county of Kane and State of Illinois, have invented certain new and useful Improvements in Folding Doors, of which the following is a specification, reference being had to the accompanying drawings.

10 My invention relates to folding doors of the type hinged together in pairs and slidably supported so as to be capable of being moved to one side of the doorway and there folded together at right angles to their former position for leaving the major portion of the doorway clear. It is the object of my invention to provide new and improved means for holding the doors normally at the side of the doorway when folded back, such means being adapted to permit a free movement of the doors again into operative closing position in the doorway when the doors are given an unfolding movement to bring them again into alignment in the doorway; to provide an improved form of caster wheel for supporting the doors, employing guiding means holding the wheel in proper operative relation to the track in which it runs; and to provide improved means for adjusting the caster vertically with respect to the door. The preferred means by which I have accomplished my objects are illustrated in the drawings and hereinafter specifically described. That which I desire to cover by this application is set forth in the claims.

In the drawings,—

Figure 1 is a view of six doors hinged together in pairs closing a doorway;

40 Fig. 2 is a horizontal section taken on line 2—2 of Fig. 1, and showing in dotted lines the position of the doors at about the close of an opening operation;

Fig. 3 is an enlarged detail, partially broken away, illustrating the doors in their open position;

Fig. 4 is a fragmentary view illustrating the means employed at the bottom of the

door for pivotally supporting the door farthest to the right in Fig. 1;

50 Fig. 5 is an edge view of one of the doors, being partly in section as seen on the line 5—5 of Fig. 1, being partly broken away for clearance of illustration;

Fig. 6 is a fragmentary view of the parts shown in Fig. 5 as seen from the right in 55 said figure;

Fig. 7 is an enlarged detail being substantially a section taken on line 7—7 of Fig. 6; and

60 Fig. 8 is an enlarged detail of the upper portion of the door and adjacent parts, partly in section, as they would appear on line 8—8 of Fig. 3.

Referring to the several figures of the drawings in which corresponding parts are indicated by the same reference characters, 65 10 and 11 indicate two doors hinged together at 12 within a doorway 13. As is best shown in Fig. 4, the door 10 is pivotally mounted 70 at its right-hand edge as shown in Fig. 1 by means of aligned pivot pins 14, the arrangement being such that the doors 10 and 11 are adapted to be moved into parallel position at right angles to their operative door-closing position. The remainder of the doorway is closed by means of doors 15 and 16 hinged together at 17 and doors 18 and 19 hinged together at 20. The left-hand edge of the door 11 and the outer edge of 75 each of the doors 15, 16, 18 and 19, are provided with supporting means as hereinafter described by which such doors are adapted to slide transversely of the doorway.

80 Each of the doors, with the exception of door 10, is provided at its outer edge with guiding means adapted to have operative engagement with a slotted track or guide extending longitudinally of the doorway at the top thereof. This guiding means comprises pins 21 rising from the doors near their edge portions and provided with rollers 22 loosely mounted thereon, the rollers 22 having a working fit between two spaced guides 23 and 24 fixedly secured in position 85 at the top of the doorway. Washers 25 are

provided on the upper ends of the pins 21 serving to hold the rollers 22 against withdrawal from the slot provided by the spaced guides 23 and 24.

5 Each of the doors except the door 10 is provided at its lower end at the free side thereof with a caster adjustably mounted upon the door for supporting the door in its sliding and turning movements. As is best
10 shown in Fig. 6, each of the casters is secured to the door by means of a bracket comprising two horizontally disposed bars 26 and 27, the bracket being secured in position by means of screws. A caster comprising a
15 housing 28 which has revolvably mounted therein a caster wheel 29 is provided with a pintle 30 which has a working fit in an opening through the bar 27 and which is adjustably and revolvably connected with the bar
20 26 of the bracket. This adjustable connection with the bar 26 is provided by the use of a collar 31 which is mounted by means of screw threads upon the pintle 30, a lock nut 32 being provided for holding the adjusting collar 31 in the desired adjusted position. The collar 31 is revolvably mounted in the bar 26 by means of a reduced portion 33 extending through a suitable opening in the bar and having a working fit therein,
25 30 a washer 34 being mounted on the upper end of the collar above the bar 26 for preventing its withdrawal. The collar 31 is provided with suitable sockets 35 in its face by the use of which the collar can be turned with
35 respect to the pintle for adjusting the caster wheel vertically with respect to the door. With the caster in position upon the door, an adjustment can be effected by the removal of either one or both of the inclosing
40 45 plates 36 which are secured in position upon opposite sides of the bracket and caster.

As is clearly shown in Fig. 7, the caster wheel 29 is revolvably mounted in the housing 28 by means of a horizontally-disposed pin 37 which supports bearing blocks 38, anti-friction devices of any suitable type being interposed between the blocks 38 and the wheel 29. The wheel 29 is adapted to bear upon the spaced bars 39 of a slotted or grooved track, a circumferential rib 40 that forms a part of the caster wheel being adapted to extend between the track portions for guiding the caster wheel upon the track. As an additional means for holding the caster wheel and the housing 28 in proper position with respect to the grooved track, I have provided a lug 41 extending downward from the housing 28 into engagement with the groove of the track. The lug 41 extends
50 55 60 downward slightly beyond the rib 40 of the caster wheel and is adapted to clear from the groove any foreign matter which might interfere with the free and easy movement of the wheel in the groove.

65 The means for holding the doors against

sliding out of their normal folded position comprises lugs 42 and 43 secured in position upon one face of and extending beyond the free edges of the doors 15 and 18, respectively, the lugs 42 and 43 being positioned 70 at the top and bottom edges respectively of the doors. These lugs extend beyond the side edges of the doors so as to be in position to contact pins 44 which are secured to the floor adjacent to the track 39 and to the 75 guide member 23 at the top of the doorway. The lugs 42 and 43 are in the same vertical plane passing outside of the door near one face thereof, and the pins 44, with which the lugs 42 and 43 of the several doors are 80 brought into contact, are in vertical alignment with each other. By this arrangement, the lugs are adapted to pass into operative engagement with the pins 44 by a smooth easy movement without any unnecessary 85 binding or clashing. By reason of the lugs 42 and 43 being upon the leading edges of the doors as the doors are moved to their normal folding position, such lugs are passed readily into contact with the pins 44 for 90 holding the doors against movement toward the left as illustrated in Fig. 2 except as the doors are again moved into alignment with each other for closing the doorway.

What I claim as my invention and desire 95 to secure by Letters Patent is—

1. The combination of a door, a grooved track, a housing pivotally mounted on said door to turn about a vertical axis thereon, a lug extending downward from said housing into the groove of said track for holding the housing in proper position with respect to the track, and a caster wheel revolvably mounted in said housing and comprising a circumferential rib engaging the groove of 100 said track.

2. The combination of a door, a bracket comprising two spaced-apart horizontal plates connected together by an attaching wall member secured to the door, a caster comprising a pintle movably mounted in the lower one of said plates, and an adjusting member having a swiveled connection with the upper plate of said bracket and having a screw threaded connection with said pintle for adjusting said caster vertically with respect to the door.

3. The combination of a door, a bracket secured thereto, a caster comprising a pintle, and a collar adjustably connected by means of screw threads with said pintle, said collar having a reduced portion at one end by which it is pivotally connected with said bracket.

4. The combination of a door, a bracket comprising two horizontally-disposed bars secured rigidly in position with respect to said door, a caster comprising a pintle having a working fit in an opening in the lower one of said two bars, and an adjusting mem-

ber having a swiveled connection with the upper one of said two bars and having a screw threaded connection with said pintle.

5. The combination of a door, a bracket comprising two horizontally-disposed bars secured rigidly in position with respect to said door, a caster comprising a pintle having a working fit in an opening in the lower

one of said two bars, a collar adjustably connected with said pintle by means of screw 10 threads and having a swiveled connection with the upper one of said two bars, and a locking nut for securing said collar against turning about said pintle.

ELLIS J. G. PHILLIPS.
